US0D1094713S

(12) **United States Design Patent** (10) Patent No.: **US D1,094,713 S**
(45) Date of Patent: ** Sep. 23, 2025

(54) **CHIRURGICAL INSTRUMENT**

(71) Applicant: **Olympus Winter & Ibe GmbH**,
Hamburg (DE)

(72) Inventors: **Roland Hopp**, Hamburg (DE); **Oliver Hahn**, Hamburg (DE); **Thomas Märzke**, Hamburg (DE); **Irina Schmuck**, Heide (DE); **Kevin Schulz**, Wilstedt (DE); **Andreas Rühs**, Ahrensburg (DE); **Bastian Schröder**, Hamburg (DE)

(**) Term: **15 Years**

(21) Appl. No.: **35/516,537**

(22) Filed: **Sep. 7, 2022**

(80) **Hague Agreement Data**

Int. Filing Date: **Sep. 7, 2022**
Int. Reg. No.: **DM/224857**
Int. Reg. Date: **Sep. 7, 2022**
Int. Reg. Pub. Date: **Mar. 10, 2023**
